UNITED STATES PATENT OFFICE.

WILLIAM HOLTON, OF ANITA, IOWA.

WEATHER-STRIP.

SPECIFICATION forming part of Letters Patent No. 393,646, dated November 27, 1888.

Application filed July 16, 1888. Serial No. 280,079. (No model.)

To all whom it may concern:

Be it known that I, WILLIAM HOLTON, a citizen of the United States, residing at Anita, in the county of Cass and State of Iowa, have 5 invented certain new and useful Improvements in Weather-Strips; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

This invention relates to weather-strips of 15 that class which have the strip hinged to the lower end of the door, and a second strip secured to the door just above the hinged strip and overlapping its top edge to shed water, &c.

20 The improvement consists in the peculiar construction of the hinged strip, the manner of connecting it with the door, its relative arrangement with the shedding-strip, and the rail for lifting the hinged strip over the carpet-strip, as hereinafter will be more fully described and claimed, and shown in the drawings, in which—

Figure 1 is a perspective view of the lower portion of a door-frame and door, showing the 30 application of my invention; Fig. 2, a vertical section on the line X-X of Fig. 1, showing the door closed; Fig. 3, a front view, parts being broken away, of the lower portion of the door having the weather-strip applied; and Fig. 4, 35 an end view showing the operation of the weather-strip by dotted lines.

The weather-strip A has a portion, *a*, of its lower edge bent outward, and a portion, *a'*, of its upper edge curved laterally in the same direction, and is secured to the door C by screws B or other fastening devices passing through slots *b*, formed in the strip at the line of flexion of the portion *a'*. By reason of the slots *b* the strip can rise and fall and accommodate 45 itself to any settling of the sill and any wear, so as to preserve a closed joint.

The shedding-strip C is secured at its upper edge to the door, and curves outward and then inward at its lower edge, which edge approaches close to the weather-strip, and is dis-

posed to come directly opposite the line of flexion of the portion *a'*, or the line of the fastening devices B, the lower edge being notched to accommodate the heads of the fastening devices B.

The weather-strip closes by gravity, and is sufficiently wide to extend over the carpet-strip D and rest on the sill. The rail E is curved, having the axis of the door for its center, and tapers from its outer end, which is 60 flush with or slightly higher than the carpet-strip D, to the plane of the floor. When the door is closing, the inner end of the weather-strip rides on the rail and carries the said strip A over the carpet-strip D. The outer end of 65 the rail terminates abruptly, and when the weather-strip reaches it and its lower edge passes beyond the said end of the rail the said lower edge of the strip falls and rests on the sill. On opening the door the end of the rail 70 will strike the weather-strip and lift it clear of the carpet-strip, and as the door is opened farther the weather-strip will gravitate as it passes over the said rail. This rail E is preferably made from a flat bar or strip of metal, 75 which is bent in the required shape, and has its end *e* bent or turned back to form a means for securing the said rail to the sill.

Having thus described my invention, what I claim, and desire to secure by Letters Patent, 80 is—

The combination, with the door, and the weather-strip having a portion of its upper edge curved laterally, and having slots in the line of flexion of the said curved portion to 85 receive the fastening devices which secure the strip to the door and which permit the said strip to have a limited vertical movement bodily, of the shedding-strip secured at its upper edge to the door and having its lower 90 edge curved outward and then inward, approaching close to the weather-strip directly opposite the said line of flexion, substantially as and for the purpose described.

In testimony whereof I affix my signature in 95 presence of two witnesses.

WILLIAM HOLTON.
